Primary Examiner — Mimosa De(74) Attorney, Agent, or Firm — Meunier Carlin & Curfman, LLC(57) CLAIM

An ornamental design for a multi-faceted display tower, as shown and described.

DESCRIPTION

FIG. 1 is a front perspective view of a multi-faceted display tower. The back perspective view, left-side perspective view, and right-side perspective view are identical to the front perspective view.

FIG. 2 is front view of the embodiment depicted in FIG. 1. The back view, left-side view, and right-side view are identical to the front view.

FIG. 3 is a top view of the embodiment depicted in FIG. 1.

FIG. 4 is a bottom view of the embodiment depicted in FIG. 1; and,

FIG. 5 is a close-up view of two rows of the embodiment depicted in FIG. 1.

The broken lines showing elements of the multi-faceted display tower in the above-described Figures are for illustrative purposes and form no part of the claimed design.

1 Claim, 5 Drawing Sheets(56)
